Primary Examiner — Sheryl Lane*Assistant Examiner* — Mark T. Philpotts(74) *Attorney, Agent, or Firm* — McAndrews Held & Malloy, Ltd.(57) **CLAIM**

The ornamental design for an air compressor, as shown and described.

DESCRIPTION

FIG. 1 is a top-front perspective view of an air compressor showing my new design;

FIG. 2 is a front elevation view thereof;

FIG. 3 is a rear elevation thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom-rear perspective view thereof.

The dashed broken lines in the figures illustrate portions of the air compressor that form no part of the claimed design.
